CLAIM

The ornamental design for an electric scooter, as shown and described.

DESCRIPTION

FIG. 1 is a perspective view of the electric scooter showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 2; and,

FIG. 12 is an exploded view of the electric scooter in which the handlebar is detached.

The dash-dot broken lines are included to annotate partial views in FIGS. 1, 2 and 9-11. All other broken lines represent portions of the electric scooter that form no part of the claimed design. None of the broken lines form a part of the claim.
